United States Patent Office

Des. 190,556
Patented June 13, 1961

190,556

COMBINED BOOK MARK AND NAIL FILE HOLDER

Willie Mae Heathman, 808 S. Kenmore Ave.,
Los Angeles, Calif.

Filed May 12, 1960, Ser. No. 60,555

Term of patent 7 years

(Cl. D6—2)

I claim:

The ornamental design for a combined book mark and nail file holder, substantially as shown.
